PROCESS AND APPARATUS FOR THE MANUFACTURE OF WIRE GAUZE

Karl Schmid, Reutlingen, Germany, assignor to firm Vereinigte Metalltuch-Fabriken Peter Villforth, Reutlingen, Germany

Application November 3, 1932, Serial No. 641,082
In Germany November 5, 1931

5 Claims. (Cl. 139—48)

In the manufacture of paper, in order to prevent the warp wires of a wire gauze serving as a paper sieve from eating into the material of the suction box, it has already been proposed to 5 arrange the warp wires of the metal gauze in an oblique direction to the direction of run of the sieve, namely preferably so that they run zigzag. An attempt has been made to obtain such a positioning of the warp wires by dis- 10 placing a wire gauze woven in the usual manner and fed to the gauze beam in alternate directions together with the beam, opposite a guide roller located over the beam.

Such a process can hardly be used in practice 15 as by the displacement of the already completely woven wire gauze in two opposite directions, a temporary distortion only of the gauze can be obtained, and not a sharply defined zigzag course 20 of the warp wires or a lasting positioning of these zigzag arranged wires. On the contrary the oblique positioning disappears in course of operation and the familiar disadvantages occur, namely the warp wires eat into the "suction covering" and there is a sharp impression of 25 the warp wires.

According to the invention, for the manufacture of a woven wire gauze, the warp wires of which are arranged slightly zigzag in the direction of the run of the gauze, all the warp 30 wires, in order that they may be fixed in a direction located slightly obliquely to the direction of run of the gauze, by alternate lateral displacement of the reed towards either direction, the warp wires are crossed at an angle deviating 35 from 90°, with the weft wires and by striking against the reed are deformed in such a manner that each warp wire is bent over the weft not vertically, but obliquely to its longitudinal direction, so that in conjunction with the marked 40 undulations of the weft wires, unlike the usual metal gauze, the warp wires are prevented from being stretched straight.

By the employment of such a process, as the warp wires rest firmly on the weft wires and 45 are relatively stiff, they are not drawn straight, but retain their zigzag positioning even in operation and after considerable use.

Consequently, the wires cannot eat into the suction covering and the resultant impression of 50 the grooves in the warp wires or sewing wires cannot occur, and the life of the paper sieve is considerably increased and also the supervision of the paper sieve is simplified, as the paper sieve thus made can easily be controlled.

55 For carrying out the process according to the

invention, it is preferable to arrange a reciprocation of the reed in the direction of the weft, which is obtained by way of an eccentric and a lever mechanism acting on the reed and which, by way of a worm mechanism, engages with a 5 shaft running in the direction of the weft, which shaft, by means of a ratchet wheel, is driven by a pawl which moves the latter further at each movement of the sley. This pawl may be attached to the loom frame and engage with the 10 ratchet wheel at each backward movement of the sley, or may be attached to the loom sley, and at each backward movement of the latter can be pressed down by a stationary stop, thereby giving the ratchet wheel a further move- 15 ment.

A typical example of the wire gauze according to the invention and an apparatus for manufacturing it are shown in the drawing, wherein:

Fig. 1 is a view of the woven wire gauze with 20 warp wires running in a zigzag direction, being somewhat exaggerated.

Fig. 2 is a view of the apparatus for moving the loom sley, seen in the direction of the weft.

As can be seen from Fig. 1, the warp wires a 25 are displaced transversely to the direction of the run of the gauze, namely towards one side and then the other. The slant of the warp wires is exaggerated and, actually, is hardly perceptible with the naked eye. The weft wires b are arranged 30 in the usual manner.

For the manufacture of such a texture, there may be used, for instance, the apparatus shown in Fig. 2.

In this apparatus the reed 2 is adapted to be 35 displaced on the sley 1 at right angles to the direction of the warp and is connected to each side of the sley by means of guide screws 3 engaging through the slot 4 of the reed. The sley is carried in a well known manner by two support 40 levers 20 that are swung to and fro. The reed is connected at either side to a tension rod 5, which is actuated by double-armed levers 6. The latter are adapted to pivot about a pin 7 connected to the sley 1, and their free ends engage with an 45 eccentric rod 8 or with a rod 9 connected with the latter, each of which is reciprocated by means of a shaft 11 and an eccentric 10. The shaft 11 is driven by way of a worm wheel 12 co-operating with a worm 13 which is mounted on a shaft 14 50 and carries a ratchet wheel 15 which on every reciprocating movement of the sley in the act of beating up the filling, is turned by a spring-controlled pawl 16. The pawl is adapted to pivot in a fork-shaped holder 17 which is attached to 55

an arm 18 that is pivotally connected to one of the support levers, i. e. the so-called lay pitmen to actuate the ratchet wheel after every time the sley at its backward movement moves out of the 5 texture. The arm 18 so far as attached to the lay pitmen may be pressed down during the returning movement of the sley by a stationary stop of the loom frame or it may be itself attached to the loom frame and engage by its 10 spring controlled pawl 16 with the ratchet wheel 15 at every backward movement of the sley.

I claim:

1. A loom for manufacturing wire gauze with warp wires that extend slightly zigzag in the 15 direction of the run of the gauze, comprising a reciprocating sley, a reed displaceable across the sley in either direction, means for slidably guiding the reed in the sley in the direction of the weft, the reed being adapted to hold all the 20 warp wires in the act of beating up the filling in a parallel position deviating at a slight angle from the reciprocating direction of the sley, a mechanism operatively connected to the movable reed and arranged to effect its lateral movement and means operated by the returning movement of the batten for actuating said mechanism.
2. A loom for manufacturing wire gauze with warp wires that extend slightly zigzag in the 30 direction of the run of the gauze, comprising a reciprocating sley, a reed displaceable across the sley in either direction, means for slidably guiding the reed in the sley in the direction of the weft, the reed being adapted to hold all the warp 35 wires in the act of beating up the filling in a parallel position deviating at a slight angle from the reciprocating direction of the sley, a lever mechanism operatively connected to the movable reed and actuated by means of a ratchet wheel, an intermediate gearing and an eccentric, said ratchet wheel being mounted on a shaft positioned 40 in the direction of the weft and cooperating with a pawl arranged on the loom frame and engaging with the ratchet wheel at every backward movement of the batten.
3. A loom for manufacturing wire gauze with warp wires that extend slightly zigzag in the 45 direction of the run of the gauze, comprising a reciprocating sley, a reed displaceable across the

sley in either direction, means for slidably guiding the reed in the sley in the direction of the weft, the reed being adapted to hold all the warp wires in the act of beating up the filling in a parallel position deviating at a slight angle from the reciprocating direction of the sley, a lever mechanism operatively connected to the movable reed and actuated by means of a ratchet wheel, an intermediate gearing and an eccentric, said ratchet wheel being mounted on a shaft positioned 5 in the direction of the weft and cooperating with a pawl adapted to pivot in a forked holder that is mounted by an arm in one of the lay pitmen and is moved down at each backward movement of the batten.

4. A loom for manufacturing wire gauze with warp wires that extend slightly zigzag in the direction of the run of the gauze, comprising a reciprocating sley, a reed displaceable across the sley in either direction, means for slidably guiding the reed in the sley in the direction of the weft, the reed being adapted to hold all the warp wires in the act of beating up the filling in a parallel position deviating at a slight angle from the reciprocating direction of the sley, a lever 20 mechanism operatively connected to the movable reed and actuated by means of a ratchet wheel, an intermediate gearing and an eccentric, said ratchet wheel being mounted on a shaft positioned 25 in the direction of the weft and cooperating with a pawl arranged on the loom frame and engaging with the ratchet wheel at every backward movement of the batten.

5. A loom for manufacturing wire gauze with warp wires that extend slightly zigzag in the 35 direction of the run of the gauze, comprising a reciprocating sley, a reed displaceable across the sley in the direction of the weft, means for slidably guiding the reed in the sley in the aforesaid direction, means for imparting a stepwise 40 predetermined lateral movement to the whole reed during every backward movement of the sley, said reed having parallel dents adapted to hold all the warp wires in the act of beating up the filling in a parallel position deviating at a 45 slight angle from the reciprocating direction of the sley.

KARL SCHMID.
